ADOLF TACCHELLA, OF ST. LOUIS, MISSOURI, ASSIGNOR TO BUSCH-SULZER BROS.-DIESEL ENGINE COMPANY, OF ST. LOUIS, MISSOURI, A CORPORATION OF MISSOURI.

INJECTION APPARATUS FOR COMBUSTION ENGINES, ETC.

Application filed January 26, 1921. Serial No. 439,896.

My invention relates to fuel injection apparatus for engines of the so-called solid injection type and more especially to the spray nozzles thereof and consists in the use of certain nozzle structures hereinafter explained for maintaining predetermined characteristics of the spray under varying engine speeds and loads, thereby improving the economy, flexibility and commercial utility of this type 10 of engine.

In engines of the kind referred to it is a matter of much importance that the fuel charge shall be injected with a proper velocity and in a state of sufficient fineness of atomization to combine effectively with the air charge and difficulty is experienced in designing the injector means so that these conditions shall be maintained under variation of the amount of fuel injected and under variation 20 of the velocity of the pump plunger or whatever means is used for impelling the fuel as well as under variation of the compression of the air charge. It is, in fact, a recognized limitation of engines which inject their fuel, 25 without the use of high pressure injecting air that their best efficiency is limited to only a narrow range of speed or load variation and the reason for this limitation is correctly assumed to be largely the effect of inadequate spraying when the speed or load has changed, 30 Efforts have been made to correct the inadequate spraying by employing injection orifices normally closed by spring seated valves but these have not proved to respond with sufficient delicacy to changes in the amount 35 of charge. I have, however, secured the requisite responsiveness and range of capacity by providing a nozzle having a normally closed, elastic and self-adjusting orifice, 40 which, yielding to the varying pressure of the charge, provides an opening exactly appropriate to it and produces a spray blast eminently suited in respect to direction and fineness of atomization to a wide range of variation 45 of engine conditions. Such an orifice has a tendency to maintain a constant or at least an adequate spray velocity for all volumes of liquid discharged and varying injection pressures, responding instantly to the pressure of 50 the charge.

Referring to the single sheet of drawings forming a part of this application, Fig. 1 is an elevation partly in section showing one embodiment of my fuel injection apparatus

in which a fuel measuring pump is employed, 55 directly associated with each injector nozzle.

Figure 2 is an enlarged detail view showing the elastic orifice and in dotted lines an exaggerated view of the elastic lips flexed outward by the passing charge. 60

Figure 3 is a section on line III—III looking in the direction of the arrows, and

Figure 4 is an elevation partly in section showing an embodiment of my invention in which the injection plunger serves also as a 65 pump and is governed controlled.

In a wall of the combustion space preferably in the cylinder head 1, is mounted the injector nozzle 2, in the body of which is a cavity in which are located the plug 70 3 and a locking plug 4 which retains the other plug in place adjustably. Back of the locking plug is a fuel chamber 5. The self-adjusting orifice is formed by the elastic seat 6 normally in contact with the surface 7 of 75 the plug adjacent its end. The elastic seat is conveniently produced by two or more cross slots 8 in the metal ring surrounding the end of the plug. The ring is thus divided into two or more flexible elastic lips. The 80 self-adjusting orifice is adapted to deliver a non-divergent and preferably a convergent spray. This is best accomplished as illustrated by making the end of the plug conical and by employing flexible elastic lips and 85 giving them an inner surface of the same form as that of the end of the plug. Constructing these contacting surfaces so that they are surfaces of revolution on the axis of the plug having converging elements results in a converging delivery of the spray 90 from each orifice and from both the opposed orifices. In order to insure the proper feed of fuel to the normally contacting surfaces of the self-adjusting orifices, I provide 95 grooves 9 slightly less than semi-annular in extent in said surfaces and located preferably in the plug near its end in a plane at right angles to its axis, so that they may be described as transverse annular grooves. 100 Fuel supply grooves 10 arranged symmetrically are provided in the plug 3 and are fed by passages 11 in the locking plug 4, preferably diverging from points near the axis of the plug toward its periphery and outer face. 105 The number of the supply grooves may be varied as may seem desirable and transverse collecting grooves 12, slightly less than semi-

annular to which passages 11 deliver may be provided in the locking plug 4, particularly where the plug 3 is provided with several supply grooves or conducting passages. 5 These details while preferred may be varied. An injection plunger 13 located in the axis of the body of the nozzle is mounted for reciprocation therein and in the oil or liquid fuel chamber 5. The customary gland 14 is 10 provided. This plunger is given reciprocation by lever 15 actuated by the usual fuel cam 16.

Different means for varying the amount of the charge may be employed. The injection 15 plunger may itself act as a pump for supplying the fuel chamber with fuel, or a separate measuring pump may be used as indicated diametrically at 17 in Figure 1, this being the preferred arrangement. This pump connected 20 with the chamber by pipe 18, valve casing 19, in which is interposed check valve 20, and passage 21 and drawing in fuel through pipe 22 may be controlled by the usual governor 23 so that the charge varies 25 with the load. With this arrangement it is not necessary to provide means for varying the stroke of the injection plunger which is moved down the full length of its stroke at each revolution of the fuel cam and is moved 30 up varying distances according to the amount of the charge supplied by the pump 17.

In the modification illustrated in Fig. 4 the injection plunger also serves as a pump and its operation is controlled by the governor 23, which through suitable connections 35 24 determines the position of the link 25 through which the fuel cam 16 operates the lever 15. In this form a spring 25 reacting against plate 26 carried by the plunger 40 and the gland bushing is provided to return the injection plunger. Of course other means for varying the charge may be used if desired.

It will be apparent that this invention increases 45 the range of speed and load variation through which the best efficiency of the engine is secured, since it insures adequate spraying throughout such increased range, adequate spraying implying maintaining the 50 requisite fineness of atomization and the proper direction and amount of the charge. The fact that the self-adjusting orifices are adapted to deliver a non-divergent spray 55 plays an important part in this result.

55 I claim:

1. A fuel injection nozzle for solid injection engines having a plug and seat members contacting therewith, one of said members being elastic and subject to deformation by pressure 60 of the fuel, the contacting faces of said plug and seat members having surfaces inclined relative to the axis of said nozzle and contacting over a considerable area and maintained in close contact subject to relative separation 65 by temporary deformation of the elastic mem-

ber by the fuel under pressure to provide between them a self-adjusting, self-closing orifice sufficient to allow the charge to pass.

2. A normally closed spraying nozzle for combustion engines having a liquid fuel receiving chamber, a plug having contact surfaces adjacent its end, separate elastic lip segments normally in contact therewith and capable of being flexed independently, transverse passages slightly less than semi-annular 75 in extent in said plug, both located in said contacting surfaces and each opposite one of said lip segments and feeding fuel to it separately, and grooves for conducting liquid fuel to said semi-annular passages, the said 80 lip segments being adapted to be separated by pressure of the charge sufficiently to let it pass.

3. A fuel injection nozzle for solid injection engines having a metal body provided with a 85 cavity extending lengthwise thereof and having a hole in its delivery end of less cross sectional area than that of the cavity, the end wall of the body adjacent the hole providing elastic flexible members integral with the 90 body and projecting therefrom longitudinally of the body and inward and having free ends, and a plug closing said hole and held in close contact with inner surfaces of said flexible members, the latter being subject to flexure 95 by the fuel under pressure to permit its injection between them and the plug.

4. A fuel injection nozzle for combustion engines having a plug having a conical end, and a seat member normally held in close 100 and extended contact with the conical surface of said end, said seat member having elastic conical segments having free ends and between which and the plug the injected fuel may force its way by momentary deformation 105 of the segments.

5. A fuel injection nozzle for combustion engines having a plug with a conical end, and flexible lips having a conical inner surface 110 with which opposite sides of the conical end of said plug are normally in contact subject to separation by fuel charges forced between them, diametrically opposite transverse liquid fuel grooves adjacent each pair of contacting surfaces, and symmetrically arranged passages for conducting liquid fuel to said transverse grooves.

6. A fuel injection nozzle for combustion engines having diametrically opposed sets of 115 normally contacting surfaces providing elastic self-adjusting and self-closing delivery orifices opened by pressure of the passing fuel charge and located to deliver converging sprays of liquid fuel injected therethrough.

7. A fuel injection nozzle for combustion engines having a plug member and a seat member having extended normally contacting surfaces inclined at an acute angle to the axis of the nozzle, said seat member being of 125 flexible elastic metal, the opposed surfaces of 130

the plug and seat being adapted to be separated by pressure of injected liquid sufficiently to let the liquid pass.

8. An injection nozzle having a body provided with a flexible elastic seat and a plug normally in contact therewith, the contacting surfaces of said seat and plug being common surfaces of revolution on the axis of the

10
plug having converging elements, said contacting surfaces being adapted to be separated by injected charges of fuel to let the same pass.

In testimony whereof, I have signed this specification.

ADOLF TACCHELLA.
